UNITED STATES PATENT OFFICE.

GEORGE H. DIEHL, JR., OF NEW YORK, N. Y.

SKIVING-MACHINE.

949,062.

Specification of Letters Patent. Patented Feb. 15, 1910.

Application filed November 7, 1908. Serial No. 461,487.

To all whom it may concern:

Be it known that I, GEORGE H. DIEHL, Jr., a citizen of the United States, residing in the borough of Manhattan of the city of New York, in the State of New York, have invented certain new and useful Improvements in Skiving-Machines, &c., of which the following is a specification, reference being had to the accompanying drawings, forming a part hereof.

This invention relates generally to machines for skiving and splitting leather, etc., in which a rotary annular knife is employed, and it relates more particularly to the means for supporting and adjusting the feed roller which co-operates with the knife.

One object of the invention is to provide for such location and relation of the feed roller with respect to the cutting edge of the annular knife as to overcome some of the difficulties which have been incidental to the use of machines of this character, and another object is to improve the structure of the devices by which the feed roller is supported with a view to securing greater efficiency and convenience in the operation of the machine.

The invention will be more fully explained hereinafter with reference to the accompanying drawings in which it is illustrated, and in which—

Figure 1 is a view, partly in plan and partly in horizontal section, of so much of a skiving machine to which the invention is applied as is necessary to enable the invention to be understood. Fig. 2 is a view of the same in front elevation, with the frame of the machine partly broken away. Fig. 3 is a detail view of the mechanism shown in Figs. 1 and 2, partly in elevation as seen from the right and partly in section.

A skiving machine of the general character of that to which the invention is applied, as shown in the drawings, comprises an annular knife *a* which is mounted upon a suitable frame *b* to rotate at high speed. Above the upper limb of this annular knife is mounted a presser foot, not shown in the drawings, and immediately below the same and upon the opposite side of the knife edge, is mounted the feed roller *c*, which is positively driven through driving means of usual character and therefore not necessary to be shown herein, such driving means, as is well understood, being of such character as to

permit bodily and angular movement of the feed roller with respect to the knife edge.

In the construction shown in the drawing, the feed roller is mounted upon a stud *d* carried by a bracket arm *e*. The latter is somewhat yoke-shaped, as clearly shown in Fig. 3, and is provided with lugs *e'* and *e''* in which are mounted pivot points *e³* and *e⁴*, the latter having a threaded stem, as shown in Figs. 1 and 3, so as to permit of easy adjustment. The pivot points *e³* and *e⁴* engage the ends of a cross-head *f* which is carried by a rock shaft *g*, the latter, in turn, being mounted between pivot points *g'* and *g''* carried by the frame *b*. A lever *h*, pivoted on the rock shaft *g*, bears at one end against an adjusting screw *h'* mounted in an arm *h²* of the rock shaft *g*, while its other end forms an adjustable point of support for a spring *h³*, the other end of the spring being connected to the swinging bracket *e* at a point about midway between its ends. An adjusting screw *i*, mounted in an arm *i'* of the rock shaft *g*, provides an adjustable stop against which the swinging bracket *e* is held by the spring *h³*. An arm *h* of the rock shaft *g* carries an adjusting screw *h'* which bears against the frame *b*, and also carries, loosely, an adjusting screw *h²* which engages a nut *h³* secured in the end of a spring *h⁴*, the other end of which is attached to the frame, as at *h⁵*.

It will now be understood that through the adjustment of the screw *i* the swinging bracket *e* is rocked about its axis to swing the roller toward or from the cutting edge of the knife, and that the pressure with which the feed roller *c* is held toward the cutting edge of the knife is regulated, independently of the position of the knife, through adjustment of the tension of the spring *h³* by the adjusting screw *h'* and lever *h*. Moreover, it will be seen that inasmuch as the adjusting screw, lever and spring are carried by the rock shaft *g* and moved with it, the adjustment of the roller with respect to the rock shaft and the adjustment of the tension of the spring are not affected by the movement of the rock shaft, as would be the case, for example, if the spring and adjusting screw were carried by the frame of the machine. Moreover, it will be seen that the axis of the feed roller carrier or swinging bracket *e*, about which the feed roller is moved by the combined

action of the adjusting screw *i* and the spring *h*³, intersects the transverse plane of the cutting edge of the knife at a point below the effective working surface of the roller (by which expression reference is made to that portion of the periphery of the roller which is directly beneath the cutting edge of the knife and in contact with the leather when the machine is in operation), or toward the center of rotation of the knife, as clearly shown by the broken line in Fig. 3, and also at a point to the right of or beyond the end of the feed roller, as clearly shown by dotted lines in Figs. 1 and 2. This relative disposition of the axis of movement of the feed roller with respect to the edge of the knife and the feed roller itself is found to secure substantial advantages in the operation of the machine, especially over machines in which such axis intersects the cutting edge of the knife itself in the plane of the end of the feed roller, as well as over machines in which such axis intersects the axis of the feed roller itself. Thus, when the axis of the carrier intersects the transverse plane of the cutting edge of the knife between the axis of the feed roller and the edge of the cutting knife, but nearer the latter and beyond or to the right of the end of the feed roller, it is possible to make a perfect skive at the right hand end of the feed roller, thus permitting the full width of the feed roller to be used and also permitting the right hand portion of the feed roller to be used in making a narrow skiving; whereas, if the axis should intersect the knife edge in the plane of the end of the feed roller, it would be impossible to make a skiving at the right hand end of the roller. The improved machine is, therefore, more flexible and convenient in operation. Again, when such axis intersects the cutting edge of the knife it is found that an abrupt shoulder is apt to be formed in the leather at the right hand edge of the skiving, whereas, if such axis intersects the transverse plane of the cutting edge somewhat within the cutting edge, then it is possible to obtain a more uniform bevel without the formation of such a shoulder. Still again, it is obvious that when the axis intersects the edge of the knife in the plane of the end of the roller, there is no possibility of yielding to accommodate an increased thickness of stock between the roller and the edge of the knife without causing a bodily movement of the roller about the axis of the rock shaft *g*; whereas, when the axis of the carrier intersects the transverse plane of the edge of the knife somewhat within the edge of the knife, there is less rigidity and increase of thickness of stock may be accommodated without requiring movement of the feed roller about the axis of the rock shaft *g*. Furthermore, it is found in practice that

when the axis of the feed roller carrier intersects the plane of the transverse edge of the knife at a point below or within the effective working surface of the feed roller, that is, toward the center of rotation of the knife, the danger of cutting off a strip of the leather of its full thickness, instead of skiving or splitting the leather, is greatly reduced as compared with former constructions. In practice, with a machine running at high speed and worked to its capacity, these advantages of operation become of substantial importance, contributing as they do to the efficiency of the machine. It will also be seen that the support of the carrier by both points upon the cross-head *f* involves less friction and less wear and tear than if a carrier shaft were extended through a shaft bearing in the cross-head and renders adjustment and replacement of parts much easier. It will also be understood that bodily adjustment of the feed roller, in a plane parallel with the axis of the annular knife, about the axis of the rock shaft *g*, is effected by the coöperation of the adjusting screw *k*² and the spring *k*⁴ and that regulation of the tension of the spring can be effected independently of the adjustment of the position of the feed roller through the provision of an independent adjusting screw *k*² for the spring *k*⁴. It will be noted, furthermore, with respect to the yoke shape of the carrier *e* that it permits the application of the spring *h*³ to the carrier about midway between its ends so that there is no tendency to twist the carrier and to make its movement hard upon its bearings, as would be the case if a carrier shaft were provided at one end with an arm to which the spring were attached.

I claim as my invention:

1. In a skiving machine, the combination of an annular knife, a feed roller, and a carrier for said feed roller mounted to swing about an axis which, when extended, will intersect the transverse plane of the cutting edge of the knife between the axis of the roller and the effective working surface of the roller and nearer such effective working surface.

2. In a skiving machine the combination of an annular knife, a feed roller, and a carrier for said feed roller mounted to swing about an axis which, extended, intersects the transverse plane of the cutting edge of the knife between the plane of the axis of the roller and the edge of the knife but nearer the latter and at a substantial distance from the end of the roller.

3. In a skiving machine, the combination of an annular knife, a feed roller, a rock shaft having a cross-head and a yoke-like carrier for the feed roller having pivot points to engage said cross-head.

4. In a skiving machine the combination

of an annular knife, a feed roller, a rock shaft, a carrier for the feed roller mounted on the rock shaft, and an adjusting screw for the carrier, a spring acting upon said carrier and adjusting means for the spring, all supported by the rock shaft.

5. In a skiving machine the combination of an annular knife, a feed roller, a rock shaft, a swinging carrier mounted on the rock shaft, an adjusting screw mounted in an arm on the rock shaft and arranged to limit the swinging movement of the carrier, a spring connected with the carrier, a lever mounted on the rock shaft and having one end connected to said spring, and an adjusting screw mounted in an arm of the rock shaft and arranged to bear against the other end of the lever.

6. In a skiving machine the combination of an annular knife, a feed roller, a rock shaft having a cross-head, a yoke-like carrier for the feed roller having pivot points for engagement with the cross-head, an ad-

justing screw to limit the movement of the carrier, a spring connected to the carrier at 25 a point substantially between its ends and out of the line of the cross head, and adjusting means for said spring.

7. In a skiving machine the combination of an annular knife, a feed roller, a rock 30 shaft having a cross-head, a carrier for the roller mounted on said cross-head, an arm extended from said rock shaft, an adjusting screw carried by said arm and arranged to bear against a fixed abutment, a spring connected at one end to a fixed support, and a second adjusting screw carried by the arm but independent of the first named adjusting screw and engaging the spring.

This specification signed and witnessed 40 this 6th day of November, A. D., 1908.
